United States Patent Office

Des. 179,669
Patented Feb. 5, 1957

179,669

SWEATER OR SIMILAR ARTICLE

Moses M. Williams, Miami, Fla., assignor of fifty percent to Radie S. Jackson, Opa Locka, Fla.

Application November 9, 1955, Serial No. 38,818

Term of patent 14 years

(Cl. D3—4)

The single figure is a front elevational view of a sweater or similar article showing my new design.

The characteristic features of the design resides in the portions shown in full lines.

The back of the sweater or similar article is conventionally plain and unornamented.

I claim:

The ornamental design for a sweater or similar article, as shown and described.
